Primary Examiner — Cynthia Ramirez

(57) **CLAIM**

I claim the ornamental design for an roll file holder, as shown and described.

DESCRIPTION

FIG. 1 shows a perspective view of a roll file holder; FIG. 2 shows a front plan view of the roll file holder; FIG. 3 shows a back plan view of the roll file holder; FIG. 4 shows a right plan view of the roll file holder; FIG. 5 shows a left plan view of the roll file holder; FIG. 6 shows a top plan view of the roll file holder; and, FIG. 7 shows a bottom plan view of the roll file holder. That which is represented by broken lines illustrates environmental subject matter only and does not form part of the claimed invention.
